UNITED STATES PATENT OFFICE.

GEORGE L. SCOTT, OF POPLAR BLUFF, MISSOURI.

INCUBATOR.

No. 875,557.

Specification of Letters Patent.

Patented Dec. 31, 1907.

Application filed January 2, 1907. Serial No. 350,373.

To all whom it may concern:

Be it known that I, GEORGE L. SCOTT, a citizen of the United States, and a resident of Poplar Bluff, in the county of Butler and State of Missouri, have invented certain new and useful Improvements in Incubators, of which the following is a specification.

My invention is an improvement in incubators, and consists in certain novel constructions and combinations of parts as will be hereinafter described and claimed.

In the drawings Figure 1 is a perspective view of an incubator embodying my invention. Fig. 2 is a vertical longitudinal section thereof, parts being shown in elevation. Fig. 3 is a vertical cross section on about the line 3—3 of Fig. 2. Fig. 4 is a perspective view showing some of the working parts, parts being broken away, and the casing 20 being indicated in dotted lines. Fig. 5 is a detail perspective view showing the end of the revolving egg holder shaft and the arm thereon. Fig. 6 is a sectional view of the egg carrier on about line 6—6 of Fig. 7. Fig. 7 is a 25 cross-section on about line 7—7 of Fig. 6. Fig. 8 is a detail perspective view of a portion of the egg carrier, and Fig. 9 is a detail perspective view showing a somewhat different construction.

In carrying out my invention I provide a suitable casing A which may be mounted upon legs B, and be supplied with doors C and D for permitting access to the lower heating compartment E, and the upper or egg compartment F. These compartments E and F may be separated from each other by a cross partition G which, as shown, may be of cotton, canvas, or other suitable fabric and extends from side to side within the casing and 35 separates the compartments E and F as will be understood from Figs. 2 and 3 of the drawings. In the lower compartment E is placed a pan or water holder E', and a heating space E² in the form of a box or recess in the bottom of said pan E' is provided, as shown in Figs. 2, 3 and 4, in which the flame from the lamp not shown, or other suitable burner may be concentrated for heating the water in the pan E'. Suitable flues e² lead 40 from the heating box E² laterally through the sides of the case and thence up to the top thereof, as shown, for carrying off the products of combustion. The heat from the water in the pan E' may circulate through

the partition sheet G and thus heat the upper compartment F. Water is supplied by a pipe from any suitable source, a valve e' being provided for regulating the same for renewing the contents of the water pan E', and a turn-cock e may be arranged as shown in Fig. 3 for drawing off the contents of the water pan when desired.

A ventilating pipe I having suitable perforations i is disposed within the compartment F at the bottom thereof, and preferably around the said compartment, as will be understood from Figs. 2, 3 and 4, for distributing fresh air supplied from the inlet pipes J communicating with the pipe I at the ends of the incubator through the openings J'. The inlet pipes J are supplied with piston valves J² actuated by springs J³, as shown in Fig. 2, the valves J² operating across the openings J'.

The valve J² it will be noticed is a piston operating in a cylinder open at its outer end and actuated by or under the influence of a spring J³, which will be compressed by the movement of the piston outwardly and expanded by the movement of the piston toward the inner end of the cylinder. The cylinder in practice is about four inches long. Cold air enters the outer end of the barrel or cylinder. When the incubator becomes heated the piston valve is gradually drawn in and opens up a space at J' through which the cold air enters the ventilator I and thence into the egg holding space of the incubator. The piston is delicate being of light material and the spring is of fine wire, as shown, so the valve piston will be acted on by the draft through the cylinder and moved to a position to nearly uncover the opening J' when the incubator is too hot and to close the said opening when the temperature of the incubator lowers, thus regulating the temperature as will be understood from Fig. 2 of the drawing.

It will be noticed from Fig. 2 that the openings J' are at the bottom of the compartment F and as the heat naturally ascends the draft will be inward through the openings J' as long as the temperature is at say 103°, which is the temperature ordinarily maintained in incubators. The draft would therefore be inward through the openings J'.

The spring J³ is of very light wire and the

piston which is also of light material is delicate in its action and is found in practice to operate efficiently for the described purpose. As the temperature rises in the incubator, 5 the draft through the ventilating pipes increases, as will be understood by those skilled in the art.

The egg carrier revolves within the upper compartment F, and has its shaft K journaled in suitable bearings K' which may be supplied with ball bearings, as best shown in Fig. 2 of the drawings, and one end of the shaft K extends through and beyond the casing and is provided with a ratchet K' engaged by a pawl L' on a swinging arm L, which swinging arm as it oscillates in the operation of the invention, as presently described, turns the shaft K in one direction and then slips back in readjusting itself in 20 the manner common to ratchet devices of the class shown.

Means are provided for actuating the egg carrier step by step and by preference water operated devices are provided for this purpose. To this end I provide a bucket M sliding vertically in suitable guides M' on the casing, and provided at its lower end with a cock or faucet, N whose handle N' is tripped by a projection a when the bucket 25 M is in its lowermost position, and it is opened to discharge the contents of the bucket M and is tripped in its uppermost position by a projection a' when the bucket is in its uppermost position to close said cock or faucet 30 35 as will be understood from Figs. 1 and 4 of the drawings. This bucket is connected by a chain O with the swinging arm L and the said arm is connected by a chain O' with a spring P above the said arm and it may be 40 guided by a guide pulley P', as shown. The purpose of this spring P is to readjust or lift the bucket M when the latter has been emptied, and a drip device Q which may be in connection with the city service or other 45 source of water supply, is arranged to drip water slowly into the bucket M so that when the latter has been lifted to the position shown in Fig. 1, and its valve closed by the projection a', the drip of water will gradually 50 fill the bucket, and the latter will lower to the position shown in Fig. 4, meanwhile giving a partial revolution to the shaft K, and the egg carriers thereon, as is desired. When the bucket M reaches its lowermost 55 position, as shown in Fig. 4, its valve will be opened by engagement with the projection a, the contents of the bucket will be discharged, and the bucket will then be readjusted by the spring P to the position shown 60 in Fig. 1, and then will be gradually moved from said position to that shown in Fig. 4, as the weight of the bucket gradually overcomes the action of the spring P, the egg carrier being thus slowly turned so that the 65 eggs will be turned gradually and without

injury, securing at the same time advantages of the turning of the eggs which is well understood by those skilled in the art.

It will be noticed on comparison of Figs. 1 and 4, that the projection A' will not turn 70 the handle N of the valve to a vertical position, but will turn it to an inclined position so that when it lowers and comes in contact with the projection a, the handle of the valve will be turned out to the position shown in 75 Fig. 4, opening the valve to permit the water to escape.

As best shown in Figs. 6, 7 and 8 the egg holder is in circular form and is provided with circular series of pockets R for the eggs, 80 said pockets being shown as short cylinders secured at one end to circular plates R' by rivets or otherwise, open at their other ends and provided at said open ends with inwardly projecting annular flanges R², to prevent the eggs from rolling out.

As shown in Fig. 2, I make the holder in sections secured along the shaft K, each section being constructed as shown in Fig. 6 with two cross plates R' spaced apart. One 90 series of pockets R is secured to one of the plates R', while the other plate R' has pockets secured on both sides, as best shown in Fig. 6, the pockets of two of the series opening toward each other as shown in Fig. 6, the 95 open ends of the opposite pockets being connected by inner and outer wire gauze sections S and S', as shown in Fig. 7. The pockets may be formed of plate material, as shown in Figs. 6, 7 and 8, or they may be of 100 wire gauze, as shown in Fig. 9. The eggs may be readily placed in and removed from the pockets and any suitable number of sections such as shown in Fig. 2 may be supplied along the shaft K.

It will be noticed from Fig. 7 that the wire gauze sections S and S' are in the form of segments of cylinders, and they inclose between them most of the pockets of the outer circular series.

In Fig. 2 the wire gauze is partly broken away so that some of the cells are shown in side view.

S, S' Fig. 7, shows wire netting projecting out between the egg cells and extending 115 around the row of cells except for an opening at one side. This wire netting is about two inches wide and when the other egg cells are shoved up to the wire it brings the adjacent sets of cells comparatively close together, see 120 Fig. 6. This allows the chicks to come out between the outer and inner sections of wire netting and when the shaft is thrust around with the opening at the bottom the chicks can fall out without injury onto the canvas 125 that separates the lower from the upper parts. This arrangement is more especially designed for incubators of large size, say in an egg holder holding 150 eggs chicks instead of slipping out and falling straight down can 130

step out and slip around to the bottom and drop through the opening. The divisions S, S', can be of wire netting or cotton cloth or tin.

5 In Fig. 9 the egg pockets are shown as formed of wire gauze T.

I claim—

1. An incubator comprising a casing having upper and lower compartments and a 10 partition sheet between the same, an egg holder in the upper compartment, means for automatically moving said egg holder, a ventilator pipe disposed in the upper compartment and having discharge openings, inlet 15 pipes communicating with said ventilator pipe, and a water pan in the lower compartment and provided in its under side with a heating space or recess and with flues leading therefrom, all substantially as and for the 20 purpose set forth.

2. An incubator comprising a casing having an upper compartment a lower heating compartment, an egg holder in the upper compartment, means for moving said egg 25 holder, and a ventilator pipe in the upper compartment below the said egg holder and disposed around the lower portion of said upper compartment, substantially as set forth.

3. An incubator comprising a casing, a revolving egg holder, and water operated means for automatically moving said holder, substantially as set forth.

4. An incubator comprising a casing, a revolving egg holder, devices for moving said 35 holder step by step, and water operated means for actuating said devices, substantially as set forth.

5. The combination in an incubator, of a casing, an egg holder, a bucket adapted to 40 contain water and having an outlet valve, said bucket being movable vertically, means for opening the valve when the bucket is in its lowermost position for discharging the contents thereof, means for filling the bucket, 45 means for readjusting the bucket to position

for refilling, and connections between the bucket and the egg holder, substantially as set forth.

6. The combination of a revolving egg holder, a swinging arm, ratchet devices between the said arm and the egg holder, a bucket connected with said arm for operating the same when the bucket is depressed, means for readjusting the bucket and arm, means whereby the bucket may be automatically emptied when it reaches its lowermost position, and means for refilling the bucket, substantially as set forth.

7. In an incubator, the combination of the casing, a revolving egg holder having its 60 shaft provided with a ratchet ring, a swinging arm having a pawl engaging said ratchet ring, a bucket connected with said arm and provided at its lower end with a discharge valve having a handle, projections for engaging and operating said handle when the bucket is in its upper and lower positions, means for filling the bucket, and a spring for readjusting said bucket and swinging arm, substantially as set forth.

8. A revolving egg holder comprising plates or carriers and pockets in the form of short cylinders whose axes are parallel to that of the holder, said cylinders being secured at one end to their respective plates or 75 carriers and open at their other ends, substantially as set forth.

9. The combination in a revolving egg holder for incubators with a plate or carrier of a series of pockets in the form of cylinders 80 whose axes are parallel with that of the revolving holder, said cylinders being secured at one end to the plate or carrier and open at their other ends and provided with inwardly projecting flanges in said open ends, substantially as set forth.

GEORGE L. SCOTT.
